UNITED STATES PATENT OFFICE.

SIMON W. WARDWELL, OF PROVIDENCE, RHODE ISLAND.

BRAIDING-MACHINE.

1,085,369.

Specification of Letters Patent.

Patented Jan. 27, 1914.

Application filed March 17, 1911. Serial No. 615,076.

To all whom it may concern:

Be it known that I, SIMON W. WARDWELL, a citizen of the United States, residing at Providence, in the county of Providence and State of Rhode Island, have invented certain new and useful Improvements in Braiding-Machines, of which the following is a specification.

My invention relates to braiding machines and particularly to the stopping and braking devices therefor shown and described in my U. S. Patent No. 1,008,504, issued November 14, 1911.

The present invention consists of certain improvements in the mechanism previously disclosed, the objects of the improvement being to render the device more effective in operation; to simplify its structure; and to cheapen the cost of manufacture.

The manner and means for accomplishing these objects are fully described in the following specification, illustrated by the accompanying drawings, in which:

Figure 1 is a plan view of the clutch-mechanism of the machine, showing the means for operating the same and also a portion of the brake-ring which co-operates therewith; Fig. 2, a side elevation of the same; Fig. 3, a detail view of the detent means for the clutch-operating mechanism; Fig. 4, a side elevation of the brake-ring, showing the actuating devices therefor; Fig. 5, a detail view of the same, part sectional on the line A—A of Fig. 4, looking in the direction indicated by the arrow x.

My improved device is adapted to be applied to a machine of the same or similar structure as that shown and described in my patent above referred to, in which the yarn supplies are carried and revolved by rotating turrets operated from a common driving shaft.

Referring to Fig. 1, 3 is the main driving shaft of the machine adapted to rotate in the horizontal bearing 4 which is preferably attached to and overhangs the base 5 of the machine frame. At the outer end of the shaft 3 is fixedly secured the clutch-member 6 through which the shaft is driven from the belt pulley 7. The clutch 6 is secured to the shaft 3 by a pin 8 projecting through a transverse hole 9 in its hub 10 and a corresponding hole 11 in the shaft. The periphery of the hub 10 is scored with a shallow groove 12 in line with one side of

the hole 9, and into this is sprung a split, wire ring 13. The pin 8 is not driven through the hub 10 and shaft 3, but has a comparatively easy fit and the ring 13 surrounds the hub and engages both ends of the pin to hold it in place. When it is required to remove the clutch from the shaft it is only necessary to spring the ring 13 out of its groove and the pin 8 can then be easily pushed out.

The clutch 6 is formed with an overhanging rim 14 having a beveled face 15 on its periphery adapted to engage the interior beveled face 16 on the rim of the pulley 7. The pulley 7 is arranged to slide on the shaft 3 to carry it in and out of engagement with the clutch 6 and is maintained in engagement therewith by a spring-pressed sleeve 17 arranged as follows: Abutting the end face 20 of the bearing 4 is a washer 21 against which the end of a coiled spring 22 bears. The spring 22 is pocketed in an annular chamber 23 extending nearly the length of the sleeve 17, and bears on the bottom of the pocket to press the sleeve in the direction indicated by the arrow a, Fig. 1. The end of the sleeve 17 abuts the hub 18 of the pulley 7 and, therefore, the action of the spring 22 is normally to maintain the pulley in engagement with the clutch 6. The pulley 7 is withdrawn from engagement with the clutch 6 by means of an arm 24 having a lug 25 at its end adapted to engage the side of a flange 26 on the hub 18. The arm 24 also has a second lug 25a adapted to bear against a flange 17a on the sleeve 17 to slide the latter away from the pulley 7 as later explained. The arm 24 slides on a guiding lug 27 which projects from the side of the bearing 4 through a slot 28 in the arm. A washer 29 secured to the lug 27 by the stud 30 retains the arm 24 in position on the lug. The opposite end of the arm 24 is connected by a pin 19 to one arm 31 of a lever 32 through which the clutch-mechanism is operated manually to start the machine. The lever 32 is also adapted to be operated from a second lever 33 actuated from the stopping mechanism of the machine and controlled by a spring 34. The lever 32 is pivoted on a stud 35 which extends upward from a boss 36 projecting from the bearing 4, see Fig. 2. The lever 33 is also pivoted on the stud 35 with its hub 37 surmounting the hub 38 of the lever 32.

100
105
110

2
To one arm 39 of the lever 33 is fastened the spring 34 which has its opposite end secured to the stud 30 extending from the bearing 4.

The two levers 32 and 33 are connected to operate together by a pin 40 extending upward from an arm 41 of the lever 32 and projecting through a hole 42 in the arm 43 of the lever 33. The hole 42 is slightly larger than the pin 40 to provide a clearance so that the lever 32 can be moved independently of the lever 33 for a purpose later explained. Pivot at the extremity of the arm 43 of the lever 33 is a pawl 44 formed with a shoulder 45 adapted to engage a corresponding shoulder on the lock-pin 46 which is driven into the bearing 4, see Figs. 1 and 3. Preferably the pawl 44 is constructed with a small piece 47 of hardened steel fastened in position with its edge forming the shoulder which engages the edge of the lock-pin 46, this construction providing against wear. The pawl 44 acts as a detent for the lever 33 to hold the latter against the action of the spring 34. A spring 48 fastened at one end to a tail 49 on the pawl 44 and at its opposite end to a lug 50 on the lever 33 acts to normally maintain the pawl 44 in engagement with the lock-pin 46. The pawl 44 is adapted to be released from the lock-pin by movement of the lever 32 as now described: Extending from the hub of the pawl 44 is a lug 51 positioned adjacent the end of the pin 40. When the lever 32 is moved manually in the direction indicated by the arrow *b* the pin 40 will engage the side of the lug 51 and rock the pawl 44 to release its shoulder from the lock-pin 46. The purpose of the clearance for the pin 40 in the hole 42 will now be evident as it will be seen that it allows the lever 32 to be moved to release the detent pawl 44 without affecting the position of the lever 33 which must remain stationary until the pawl is disengaged from the pin 46. The detent pawl 44 is also adapted to be released through instrumentalities actuated by the stopping-devices of the machine, controlled by the yarns delivering to the braid, as next described. As more fully shown and described in my patent before referred to the rotation of the turrets is checked after the disconnection of the driving means by a normally stationary brake-ring 55 mounted on the base 5 of the machine frame. The ring 55 is adapted to be moved rotatively on its bearing 56, see Figs. 4 and 5, by means operated by the yarn-controlled drop-wires which coact with the feeler-levers 57.

The arrangement of drop-wires for the yarns is shown and described in my pending application, Serial No. 605,266, filed January 28th, 1911, and will not be here described in detail as it is sufficient to explain that when a drop-wire is released by the yarn it operates the feeler levers 57 as next described.

Referring to Fig. 4, 60 designates a bracket which is mounted on the turret 61 and revolves about the axis of the machine in the direction indicated by the arrow *c*. There are several of these brackets arranged around the machine, generally an equal number to the number of supply cops of yarn employed, as more fully shown and described in the application last referred to, and each bracket carries a feeler lever 57. 70 The lever 57 is preferably pivoted at 58 to adapt its end to be tilted downward into the path of the brake-arm 62. The arm 62 is pivoted at 63 on the base 5 of the machine frame and preferably there is the same number of brake-arms as there are brackets spaced equidistantly around the machine. The arm 62 is connected to move the brake-ring 55 by means of a stud 64 screwed into the ring with its head 65 projecting through a slot 66 in the arm. The arm 62 is preferably constructed of sheet metal with its upper end twisted at right-angles to the body portion to form the head 67, see Fig. 5. The brake-ring 55, as before explained, is mounted on the flange or bearing 56 and is formed with an interior beveled face 68. The bevel 68 is adapted to be frictionally engaged with an oppositely beveled face 69 on the rotating turret 61. This engagement is effected by 90 the rotary movement of the ring which causes it to be raised from its bearing 56 as now explained: Fastened to the ring 55 is a wedge-block 71 which is formed with a beveled face 72 adapted to engage an oppositely beveled face 73 on a projection 74 of the wedge-block 75, the latter being secured to the base 5 of the machine frame. 100

The wedge-blocks 71 and 75 are constructed and secured in position in a novel manner as now described: Both the ring 55 and base 5 are provided with circumferentially extending grooves, designated 76 and 77, respectively, and the wedge-blocks 71 and 75 are formed with projections or 110 splines fitted to these grooves. Preferably the wedge-blocks are constructed of sheet-metal and the projections are formed by indenting the metal on one side to force it out on the other. In this way the projections 78 and 79, see Fig. 5, are formed at the same operation as the stamping out of the blocks by the employment of suitable punches and dies in a usual form of drop-press. The block 75 is secured to the base 120 5 by a screw 80 and the two projections 79, spaced some distance apart and fitting the groove 77, hold the block from turning on the screw. The arm 62 is preferably pivoted on the block 75 by the rivet 63 to obviate 125 the necessity of tapping a hole in the base 5. The block 71 is secured to the brake-ring 55 by the same stud 64 which engages the slot in the arm 62. The shank of the stud 64 extends through a slot 81 in the 13

wedge-block 71 and its head is screwed against the face of the block to bind the latter against the ring 55. The slot 81 allows the block 71 to be adjusted laterally in relation to the block 75, so that the beveled faces 72 and 73 may be set to engage each other at the proper time, and, as in the case of the block 75, the projections 78 fitted to the slot 76 prevent the block 71 from turning on the stud 64. It will be seen that the novel construction just described shows marked improvement over that disclosed in my patent first referred to herein, as the parts are much simpler and can be manufactured at less cost. Furthermore, only two screws are necessary for the whole arrangement described, one of them being adapted to serve two purposes.

As before stated, the brake-ring 55 is initially operated from the turret 61 through the engagement of one of the levers 57 with one of the arms 62. A slight rotary motion is given to the brake-ring by the prying action of the arm 62 as the lever 57 wipes across its upper end and this movement of the ring is adapted to release the detent means for the clutch-mechanism as now described.

Referring to Fig. 1, a tripping element 85 is secured to the periphery of the brake-ring 55 by the screws 86 extending through the flange 95 and is formed with an inclined portion 87 extending adjacent the extremity of the detent pawl 44. As the ring 55 is moved rotatively in the direction indicated by the arrow *c*, the curved edge 88 of the member 85 engages the rounded end of the pawl 44 and forces it outward to release its shoulder from the lock-pin 46. The pawl 44 is pivoted on a pin 89 extending upward from the arm 43 of the lever 33 and screwed into the end of this pin is one end 90 of a wire staple 91, see Figs. 1 and 3. The other leg 92 of the staple 91 engages a slot 93 in the projecting portion 87 of the member 85. A hairpin-shaped spring 94 is secured to the member 85 with one end 96 extending down through a hole in the latter and the loop portion 97 abutting the flange 95. The opposite end of the spring 94 is coiled around the leg 92 of the staple 91 and the tendency of the spring is to normally maintain the staple 91 at the end of the slot 93 in the position illustrated in Fig. 1.

Having now described the construction and arrangement of the parts in detail the method of operation of the whole device will next be explained: To start the machine the lever 32 is moved in the direction opposite to that indicated by the arrow *b*, Fig. 1. The arm 41 of the lever 32, carrying the pin 40, will then act through the latter to move the lever 33 to slide the member 24 in the direction indicated by the arrow *a*. This movement carries the lugs 25 and 25^a on the

arm 24 away from the flange 26 of the driving-pulley 7 and the flange 17^a on the sleeve 17, respectively, so that the spring 22, acting through the sleeve 17, forces the pulley into engagement with the clutch 6. During the movement of the lever 33 to release the driving-pulley the pawl 44 is carried into position to allow its shoulder 45 to engage the lock-pin 46 and such engagement is effected by the action of the spring 48 tending to swing the end of the pawl toward the pin. The engagement of the pawl with the lock-pin holds the lever 33 against the tension of the spring 34, and it will be noticed that the lugs 25 and 25^a are then free of the flanges 26 and 17^a so that the pulley 7 and sleeve 17 rotate without frictional contact with the arm 24. The sleeve 17, pulley 7 and clutch 6 will rotate as a unit with the shaft 3 and the latter is thereby driven from the belt on the pulley to operate the machine.

When it is desired to stop the machine by manual control the lever 32 is pressed in the direction indicated by the arrow *b*, Fig. 1. The first movement of the lever 32 will carry the pin 40 against the lug 51 on the pawl 44 and the latter will be rocked thereby to disengage its shoulder from the lock-pin 46. The release of the pawl 44 allows the lever 33 to be moved under action of the spring 34, and, through the pin 40, the movement of the lever 32 is continued to slide the arm 24 in the direction opposite to that indicated by the arrow *a* to withdraw the pulley 7 from the clutch 6. It is called to attention that there is less clearance between the lug 25^a and the flange 17^a than there is between the lug 25 and flange 26 when the arm 24 is in the position illustrated in Fig. 1, with the pulley 7 in engagement with the clutch 6. This is to provide that when the arm is moved in the direction just described its action will be to first cause engagement between the lug 25^a and flange 17^a, before the lug 25 engages the flange 26. The purpose of this is to move the sleeve 17 away from the end of the hub 18 of the pulley 7 and after this action the sleeve and pulley are both moved together. In this way the sleeve 17 is held from frictional engagement with the hub of the driving-pulley while the shaft 3 is at rest and consequently the constant rotation of the pulley will not cause wear on the end of the sleeve.

To stop the machine automatically upon the breakage or exhaustion of a supply yarn the mechanism operates as follows: Referring to Fig. 4, the feeler-lever 57 is adapted to be tilted into position to bring its lower end into the path of the brake-arm 62 by the action of the drop-wires, not here shown. When one of the levers 57 is so actuated its movement with the turret in the direction indicated by the arrow *a* causes it to wipe

across the top of the arm 62 and the latter will be swung in the direction indicated by the arrow *d*. This movement of the arm 62 5 dispenses the brake-ring 55 rotatively a short distance around the base 5 of the machine frame and carries the member 87 against the end of the detent-pawl 44, see Fig. 1, to disengage the latter from the lock-pin 46. Immediately the pawl 44 is released the lever 33 10 will be operated to disconnect the driving pulley 7 from the clutch 6, as previously explained, and this movement of the lever under action of its spring 34 acts to continue the rotative movement of the brake-ring. 15 When the lever 33 is moved by the spring 34 the staple 91 engaging the slot 93 in the member 85 will exert a pull on the brake-ring to continue the movement of the latter in the direction indicated by the arrow *c*, 20 Fig. 1. The initial movement of the brake-ring from the arm 62 brings the beveled faces 72 and 73 of the wedge-blocks 71 and 75 into contact and when the movement of the ring is continued the engagement of the wedges 25 forces the ring 55 bodily upward to bring its beveled face 68 into frictional engagement with the face 69 on the turret 61. There being a plurality of the pairs of 30 wedge-blocks spaced equidistantly around the machine, the brake-ring will be carried up evenly to effect a firm engagement with the turret. Furthermore, as the brake-ring becomes firmly engaged with the turret the latter will have a tendency to rotate the ring 35 in the same direction and this intensifies the thrust of the wedge-blocks so that a cumulative braking force is secured.

The purpose of the spring 94 on the member 85 is to act as a buffer or shock-absorber 40 to prevent injury to the operator's hand when the machine is being started manually. Sometimes when the machine is first started, before the yarns are under proper tension, a slack yarn will allow its drop-wire to remain 45 depressed and this in turn causes one of the levers 57 to remain in the path of the arms 62. The operator's hand is held on the lever 32 for a moment after the machine is started to insure that the stopping-mechanism will 50 not act to release the detent pawl should a lever 57 engage an arm 62 and if such engagement occurs the ring 55 will be given a slight thrust around its bearing on the machine frame. The force of this thrust is 55 taken up by the spring 94 which yields sufficiently to allow the movement of the brake-ring without forcing the lever 33 rigidly against the operator's hand. It will be understood, however, that the spring 94 is stiff 60 enough to move the brake-ring back into its initial position when the lever 33 is shifted by the lever 32 to start the machine.

It will be obvious that various modifications might be made in the form and arrangement of my mechanism for adapting

the improvements shown to different structures of machines.

Therefore without limiting myself to the exact construction shown, what I claim is:—

1. In a braiding machine, the combination with a rotating turret, of a brake-ring adapted to engage said turret, automatically-operated means to rotate the ring to bring it into engagement with the turret, manually-operated means to return the ring to its initial position, and resilient means between the ring and the manually-operated means to prevent shock on the latter when the rotating means for the ring are operated during its manual operation. 70

2. In a braiding machine, the combination with a rotating turret, of a brake-ring adapted to engage said turret, automatically-operated means to rotate said ring, means brought into engagement by the rotation of the ring to carry the latter into engagement with the turret, manually-operated means to return the ring to its initial position, and a spring connecting the ring with said manually-operated means to prevent shock on the latter when the ring is rotated against the action of the manual means. 85

3. In a braiding machine, the combination with a rotating turret, of a brake-ring adapted to rotate in the direction of the turret, automatically-operated means to move the brake-ring rotatively from the turret, means actuated by said ring in its rotation to carry the brake-ring into engagement with the turret, manually-operated means to return the ring to its initial position, and a spring interposed between the ring and said manually-operated means to prevent shock on the latter when the ring is moved from the turret. 95

4. In a braiding machine, the combination with a rotating turret, of a brake-ring adapted to rotate in the direction of the turret, automatically-operated means to rotate the ring, wedges brought into engagement by the rotary movement of the ring to carry the latter into engagement with the turret, means to operate the ring to remove the wedges from engagement, and a spring interposed between said means and the ring to prevent shock on the former when the ring is rotated against the action of said means. 110

5. In a braiding machine, the combination with a rotating turret, of a brake-ring adapted to be engaged with said turret, automatically-operated means to engage said ring with the turret, manually-operated means to release said ring from the turret, and resilient means connecting the ring with said releasing means to prevent shock on the latter during the manual operation of the ring. 120

6. In a braiding machine, the combina- 130

tion with a rotating turret, of a brake-ring adapted to be engaged with said turret, automatically-operated means to engage said ring with the turret, detent means to prevent the operation of said ring, means to release the ring from engagement with the turret and to lock the detent means, and resilient means connecting the brake-ring with the releasing means to prevent shock on the latter during manual operation.

7. In a braiding machine, the combination with a rotating turret, of a brake-ring adapted to engage said turret, automatically-operated means for engaging the ring with the turret, a lever to operate said ring, a detent to hold said lever from operation, means connecting said lever to move the ring, and a spring interposed between said means and the ring to prevent shock on the lever when the ring is moved against the action of the lever during manual operation of the latter.

8. In a braiding machine, the combination with a rotating turret, of a brake-ring adapted to be moved in one direction to

cause it to engage the turret, automatically-operated means for moving the ring to engage it with the turret, a lever connected positively to the ring to move the latter manually to engage the turret, and resilient means between the lever and the ring to adapt the ring to be moved in the opposite direction through manual operation of the lever.

9. In a braiding machine, the combination with a rotating turret, of a brake-ring adapted to engage said turret, automatically-operated means for effecting such engagement, a lever 33 for manually operating the ring, a member 91 connecting said lever with the ring, and a spring 94 arranged to take the thrust of the ring against the lever.

In testimony whereof I affix my signature in presence of two witnesses.

SIMON W. WARDWELL.
